UNITED STATES PATENT OFFICE.

HANS E. DINESON, OF BRIDGEPORT, CONNECTICUT, ASSIGNOR, BY MESNE ASSIGNMENTS, TO MAURICE SCHOLMAN, OF BRIDGEPORT, CONNECTICUT.

ELECTRICAL WATER HEATER.

Application filed June 11, 1926. Serial No. 115,181.

This invention relates to an electrical water heater, and an object of the invention is to provide a water heater having several features and characteristics of construction which are improvements over the disclosure of the prior art, specifically over the U. S. Patent to Nichols, No. 1,056,205, granted March 18, 1913.

A more specific object is to provide an electrical water heater including a member having a tortuous water passage the whole of which is adapted to always contain water, and a resistance device adapted to extend uninterruptedly throughout said tortuous water passage.

A further specific object is to provide an electrical water heater including a member having a tortuous water passage, a resistance device fitted in said passage, and means at the outlet of said passage for controlling the flow of water from said member, whereby to insure that said passage can at all times be full of water.

A further specific object is to provide an electrical water heater including a member having a tortuous water passage, a resistance device extending uninterruptedly throughout the length of said passage, means at the inlet of said passage to control the flow of water under pressure to said passage, means at the outlet of said passage for controlling the flow of water from said passage, and an arrangement for actuating both of the means to close both the inlet and outlet of said passage simultaneously, whereby to insure that said passage will at all times be full of water.

With the above objects in view, as well as others which will appear as the specification proceeds, the invention comprises the construction, arrangement, and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the appended claims.

In the accompanying drawing forming a part of this specification,

Fig. 1 is a sectional side elevational view of an electrical water heater in which the features of the invention are incorporated;

Fig. 2 is a sectional view as on line 2-2 in Fig. 1;

Fig. 3 is a sectional view as on line 3-3 in Fig. 1; and

Fig. 4 is a sectional diagrammatic view. 60

With respect to the drawing, 10 denotes a member having a continuous tortuous passage 11 for water, said member being of any suitable material and shape, but being of non-conducting material. As disclosed, the member 10 is cylindrical and is of porcelain. The entrance of the member 10 to the passage 11 is indicated at 12, and the exit from said passage is represented at 13. The continuous tortuous water passage 11 includes a plurality of ducts 14 connected at their tops and bottoms by grooves 15 disposed in alternation in the top and bottom of the member 10. The ducts 14 are preferably in parallelism, and are located at different distances from the axis of the member 10. 70

Surrounding the member 10 is a casing 16 which is generally, although not necessarily, made of metal, the casing extending above the upper end of the member 10 and having a removable screw cap 17. The lower end of the casing 16 extends below the member 10 and has a removable shell 18 threaded thereto provided interiorly thereof with a partition 19. Fitted within the casing 16 are plates, each denoted 20, made of some insulating material. Packings 21 are interposed between the plates 20 and the member 10, and packings 22 are located between the upper plate 20 and the cap 17 and between the lower plate 20 and the partition 19. The two plates 20, the partition 19 and the member 10 are preferably tied or rigidly connected together, and for this purpose tie rods or bolts 23 may be utilized, the bolts 95 extending through registering openings in the several parts. In addition to the tying function, the bolts also serve as binding posts as will hereinafter appear. 90

For the purpose of heating the water in the continuous tortuous passage 11 through the member 10 I provide a resistance device such as that denoted at 24. This resistance device is a continuous coil extending the full length of the tortuous passage 11, from the entrance 12 of said member 10 to the exit 13 thereof, the whorls of the coil lying in all of the ducts 14 as well as in the grooves 15. See Figs. 1, 3 and 4. The terminals of the resistance coil 24 are, as shown in Fig. 4, connected with the 110

2

lower ends of the binding posts or tie rods 23. The partition 19 is provided with the pendent valve body 25, the two parts being integral, and the valve body has an opening 26 in which the water supply pipe 27 is tapped. Leading oppositely from the opening 26 are channels 28 and 29 which are connected by ports 30 and 31 with chambers 32 and 33 formed in the valve body 25 all as indicated in Fig. 1. Conforming to ports 30 and 31 are valves 34 and 35 which are of plug and tapered type and do not need to be further specifically described. The two valves 34 and 35 are normally held in their closed positions by springs each designated 36 and bearing respectively against nuts 37 tapped into the lower part of the pendent body 25. The two valves 34 and 35 are opened by being thrust downward, and the means for opening the said valves consists of a spindle or stem 38 supported by a faucet 39 and by a plug 40 threaded into the rear part of the pendent body 25, the spindle or stem having an operating handle 41, and cams 42 and 43, the cam 42 being adapted to open the valve 34 and the cam 43 being adapted to open the valve 35. It will be evident that when the tapered portion of the valve 34 is moved below the channel 28, water can flow from said channel by way of the port 30, into the chamber 32, and the statement applies with respect to the valve 35 and chamber 33. The amount of water to be delivered can be gaged by the degree of movement of the two valves which are alternately opened. In the lower plate 20 is a channel 44 the outer or lower end of which is in register with a port 45 extending through the partition 19 and lowermost packing 22 and communicating with chamber 32, while the upper end of said channel 44 is connected with the entrance 12 of the passage 11. The exit 13 of the passage 11 is connected by a port 46 through the lower plate 20 with a channel 47 in the valve body 25, said channel leading to a cavity 48 having a valve 49 desirably constructed and seated in the same manner as the valves 34 and 35. The valve 49 conforms to a port 50 connecting the cavity 48 with a chamber 33, and said valve 49 is adapted to be opened by a cam 51 upon the spindle or stem 38 which acts to open said valve and allow the same to close simultaneously with the opening and closing of the valve 34. When the valves 34 and 49 are opened, water will flow from the channel 28 to the chamber 32 by way of the port 30 passing through the port 45 into the channel 44 and thence into the passage 11. Such water will then traverse the continuous tortuous passage and pass from the passage by way of the port 46, the channel 47, the cavity 48, the port 50, the chamber 33, and out the faucet 39 for consumption. It will be assumed at this time that current is traversing the coils of the resistance member 24, and owing to this condition the water as it flows through the passage 11 will be heated by the whorls. On allowing the valves 34 and 49 to close the flow of water will cease, and by allowing said valves to close simultaneously, or the valve 49 to close first, an arrangement is, obviously, provided whereby the continuous tortuous passage 11 will always be full of water and all of the whorls of the resistance coil will be submerged. On opening the valve 35, water from the channel 29 can flow into the chamber 33 and then through the faucet 39, and in this latter case the water is not brought into contact with the whorls of the resistance device. To prevent water passing directly between chamber 32 and chamber 33, the stem 38 may be provided with a tapered valve 52 constantly held against a seat in the partition or wall 53 separating said chambers 32 and 33.

The device in practice involves an electric switch necessary to be only partially shown and briefly described.

Fastened in some suitable manner to the rear part of the shell 18 is a casing 54 which contains the switch mechanism and certain other electrical connections. From the lower ends of the rods 23 the wires 55 extend being connected within the casing 54 to terminals 56 generally made in the form of clips, and which cooperate with clips 57 also located in said casing 54 and which are wired or otherwise connected by wiring denoted in a general way by 58 with a suitable source of electrical current. The switch which cooperates with the two sets of contacts 56 and 57 is denoted in a general way by 59, being of the double armed construction and being rigidly fastened to the shaft 60 mounted in the casing 54. Said shaft also rigidly carries a spur gear 61 in mesh with a practically similar spur gear 62 and cooperative with a mutilated pinion or segment 63, fastened to the stem 38. The shaft of the lower gear 62 is surrounded by a coil spring 64, the function of which is always positively to move the switch 59 to its circuit-breaking position at which time it bears against a stop 65 in the casing 54 as indicated in Fig. 4. As intimated the resistance circuit is shown broken in Fig. 4, the handle or lever 41 at this time being in its downward position, valves 34, 35 and 49 being closed. To secure a flow of cold water, the handle 41 is swung up to the dotted line position to the left in Fig. 4, and on this motion the teeth of the mutilated pinion or segment 63 will not be brought into mesh with the spur gear 62. The valve 35, however, will be opened by the cam 43 so as to obtain a supply of cold water. The parts are so proportioned that the said handle or lever 41 can be moved to its upper vertical

position without bringing the teeth of the mutilated pinion or segment 63 into mesh with those of the spur gear 62, and I might add that when said handle is in said upper position, the active part of the cam 43 will have passed out of engagement with the valve 35 whereby the latter will be closed. To obtain a supply of hot water the handle 41 will be swung over to the dotted line position to the right in Fig. 4 and during this action the teeth of the mutilated pinion or segment 63 will be brought into mesh with the spur gear 62 thereby turning said spur gear 62, the latter consequently turning the spur gear 61 so as to cause the branches or arms of the switch 59 to bridge the two sets of contacts 56 and 57, and thereby cause the current to traverse the whorls of the resistance member 19 and hence heat the water, it being understood that when the switch is thrown to its circuit closing position, the cams 42 and 51 will open the valves 34 and 49. To cut off the supply of hot water, the handle 41 will be returned to either of the other described positions and during the reverse motion of said lever, the switch 59 by the described gearing, is returned to its circuit opening position. In case there should be any drag from any cause, the spring 64 will positively move said switch to its ineffective or circuit breaking position.

What I claim is:

1. An electric water heater comprising a member having a tortuous water passage, a resistance device in said passage, means to control the flow of water from said passage, means to control the flow of water under

pressure to said passage, and mechanism for actuating both of said means to simultaneously cut off the flow of water to and from said passage. 40

2. An electric water heater comprising a member having a tortuous water passage, a resistance device extending uninterruptedly through said passage, means to control the flow of water from said passage, means to control the flow of water to said passage, and mechanism for actuating both of said means to simultaneously cut off the flow of water to and from said passage. 45

3. An electric water heater comprising a member having a tortuous water passage, a resistance device in said passage, a valve body having a chamber with which said passage is adapted to communicate, a faucet 55 with which said chamber communicates, a water inlet adapted to communicate directly with said chamber and to communicate with said chamber via said passage, means for controlling the flow of water from said inlet 60 directly to said chamber, and means for controlling the flow of water from said inlet via said tortuous water passage to said chamber, said last mentioned means being situated between said tortuous water passage 65 and said chamber.

4. The combination as specified in claim 3, wherein the resistance device has coils extending uninterruptedly in said passage.

Signed at Bridgeport, in the county of 70
Fairfield and State of Connecticut, this 8th
day of June, A. D., 1926.
